UNITED STATES PATENT OFFICE.

BENJAMIN F. SISSON, OF MINNEAPOLIS, MINNESOTA.

EXPANDING REAMER.

SPECIFICATION forming part of Letters Patent No. 245,023, dated August 2, 1881.

Application filed May 9, 1881. (No model.)

To all whom it may concern:

Be it known that I, BENJAMIN FRANKLIN SISSON, a citizen of the United States, residing at Minneapolis, in the county of Hennepin and State of Minnesota, have invented a certain new and useful Improvement in Expanding Reamers, of which the following is a specification.

This invention relates to that class of implements known as expanding reamers; and it consists in a reamer formed with slits cut through its upper part, and with a conical interior adapted to be drawn down over a conical mandrel to expand the reamer so as to increase its diameter or restore its former size when worn, as hereinafter set forth. I attain these objects by the use of the mechanism illustrated in the accompanying drawings, in which—

20 Figure 1 is a partly-sectional side view. Fig. 2 is a complete side view, and Fig. 3 is a top-plan view.

A is a hollow reamer, provided with the cutting ribs or faces *a* in the ordinary manner, and 25 with the upper part of the interior slightly conical and adapted to fit down over a somewhat larger conical mandrel, B, to which it is coupled or otherwise secured by pins or lugs *b*, so as to be revolved therewith.

30 *c c c c* are slits cut through the upper part of the reamer, except small portions at *d*. When the reamer is first formed and the slit *c* cut therein it may be used as an ordinary reamer until it becomes dulled and requires regrounding. This of course reduces its size; hence to 35 restore its size a wedge-shaped plug is driven into the hole *e* in the upper end of the reamer until one of the solid portions *d* is split open. Then a screw, *g*, is inserted through the hole 40 *e* and the mandrel B drawn up into the reamer

A, the screw having previously been tapped into the upper end of the mandrel. This will expand the reamer by means of the slit *c*, extending below the part *d* that has been broken by the wedge-shaped plug, and if a greater 45 degree of expansion is required two or more of the parts *d* may be split open. By this means the reamer may be expanded to any desired extent within the limits of the strength of the metal.

50 Between the top of the mandrel B and the inside of the hollow reamer A washers *h* of varying thicknesses will be placed, so that the reamer may be expanded to any desired degree, as it will be readily seen that if a thin 55 washer be placed in the mandrel the reamer will be drawn down over the mandrel more than if a thick washer were used; hence the size of the reamer may be perfectly regulated by the thickness of the washers used.

50 What I claim as new is—

1. An expanding reamer consisting of a fluted or grooved shell, A, conical within its interior, and having slits *c* cut through its body except at its outer end, where they extend but partially therethrough, and a conical mandrel, B, whereby the parts are adapted to operate as set forth.

2. The combination and arrangement of the fluted or grooved reamer A, provided with the 65 slits *c* and made conical on the interior, and the conical mandrel B, and regulating-washer *h*, and screw *g*, substantially as set forth.

In testimony whereof I have hereunto set my hand in the presence of two subscribing witnesses.

BENJAMIN FRANKLIN SISSON.
